UNITED STATES PATENT OFFICE

EDWARD E. JOHNSON, OF ST. PAUL, MINNESOTA, ASSIGNOR TO EDWARD E. JOHNSON, INCORPORATED, OF ST. PAUL, MINNESOTA, A CORPORATION

COUPLING

Application filed October 18, 1923. Serial No. 669,441.

My invention relates to couplings, and has for an object to provide a coupling having wings adapted to clasp and be secured to wooden rods or shafts such as pump rods. 5 My improved coupling may be economically manufactured by providing two strips of sheet metal, bending the end portions of both of the strips to form wings, placing the middle portions of the strips in contact with each other with the wings of one strip positioned at right angles to the wings of the other strip to produce a socket and securing the middle portions together.

The full objects and advantages of my invention will appear in connection with the detailed description, and the novel features of my inventive idea will be particularly pointed out in the claims.

In the drawings which illustrate the manufacture of my coupling,

Fig. 1 is a face view of a strip of sheet metal. Fig. 2 is a face view of another strip of sheet metal. Fig. 3 is a view in so-called perspective showing the coupling which is 25 produced by bending the end portions of the two strips to form wings and securing the middle portions of the strips together. Fig. 4 is a side elevational view of a tubular attaching member which may be employed to 30 secure the strips together. Fig. 5 is a plan view of said tubular member. Fig. 6 is a sectional elevational view showing the strips secured together by another form of attaching member. Fig. 7 is an elevational view 35 showing the manner in which two wooden rods may be secured together by using two of the individual couplings.

In carrying out my invention, two strips 10 and 12 are cut to the desired size from 40 sheet metal, the strip 10 being preferably considerably longer than the strip 12. The two end portions of the strip 10 are provided with holes 14, 16, 18, and 20, and this strip is provided centrally with an elongated opening 22 45 which is shown squared on two opposite sides. The two end portions of the strip 12 are provided with holes 24 and 26 and this strip is provided with an elongated opening 28 which 50 is like the opening 22 but extends longitudinally while the opening 22 extends trans-

versely. At equal distances from the central opening therein, the strip 10 is bent at right angles on the lines 30 and 32 to form wings 34 and 36, thus leaving the middle portion 38. The strip 12 at equal distances from the central opening therein is bent at right angles on the lines 40 and 42 to form wings 44 and 46, thus leaving the middle portion 48. The middle portions of the two winged members thus produced are placed in contact with each other with the wings of one strip positioned at right angles to the wings of the other strip to produce a socket. It is obvious that when this is done, the two openings 22 and 28 will exactly coincide or register 55 with each other. The contacting middle portions 38 and 40 may be secured together in any suitable manner for the purpose of forming a coupling. For this purpose a tubular attaching member 50 shown in Figs. 4 and 5 60 may be employed. This member is internally threaded and its closed end is provided with an axially extending lug 52 which is properly shaped to fit into the registering openings 22 and 28. The lug is then headed down as indicated at 54 in Fig. 7, the shape of the lug 65 and openings preventing relative turning of the parts. In Fig. 6, the contacting portions 38 and 48 are shown secured together by means of an externally threaded cylindrical member 56 having a head 58 provided with an axially extending lug 60 which extends only into an opening in the portion 38. The portion 48 is therefore in this form left unprovided with an opening so that the end of 70 the lug 60 butts against the surface of this portion. The member 56 is secured by welding the head 58 and the lug 60 to the contacting middle portions 38 and 48. Fig. 7 75 shows how two square rods or shafts may be secured together by means of the two couplings shown in Figs. 3 and 6, the screw-threaded member 56 being screwed into the threaded recess in the tubular member 50. As shown in Fig. 7, the couplings are secured to square 80 wooden rods such as 62 by rivets 64 passing through the holes in the winged strip 10 and by a rivet 66, passing through the holes in the winged strip 12. It is obvious that the internally threaded tubular member 50 may 85

90

95

100

be used to secure the externally screwthreaded end of a metal rod and that the externally threaded cylindrical member 56 may be used to receive the internally threaded end of a metal tube. My method provides a very strong and effective coupling which is much less liable to break in use than castings since the rolled or drawn metal which I employ is tough and ductile enough to permit considerable flexing without breaking.

I claim:

1. A coupling comprising a relatively long strip of sheet metal, a relatively short strip of sheet metal, said strips having their end portions angularly positioned to form wings, the middle portions of the strips being in contact with each other with the wings of one strip positioned at right angles to the wings of the other strip to produce a socket, and means for securing said middle portions together.
2. A coupling comprising two strips of sheet metal having their end portions angularly disposed to form wings, the middle portions of the strips being in contact with each other with the wings of one strip positioned at right angles to the wings of the other strip to produce a socket, at least one of said strips having an elongated opening at its middle, and a rod attaching member having a lug of elongated cross-section secured in said elongated opening.
3. A coupling comprising two strips of sheet metal having their end portions angularly disposed to form wings, the middle portions of the strips being in contact with each other with the wings of one strip positioned at right angles to the wings of the other strip to produce a socket, one of said strips having an elongated transversely extending opening at its middle and the other of said strips having an elongated longitudinally extending opening at its middle, and a rod attaching member having a lug of elongated cross section secured in said openings when registered with each other.
4. A coupling comprising a base having an elongated opening at its middle, four side members extending at right angles to each other successively and at right angles to said base to form a socket, and a rod attaching member having a lug of elongated cross-section secured in said opening.

In testimony whereof I hereunto affix my signature.

EDWARD E. JOHNSON.
